(57) **CLAIM**

The ornamental design for display screen or portion thereof with a transitional graphical user interface, as shown and described.

DESCRIPTION

FIG. 1 is a front view of a first image of a display screen or portion thereof with a transitional graphical user interface showing the new design; and,

FIG. 2 is a second image in a sequence thereof. Within the drawings, the appearance of the transitional image sequentially transitions between the embodiments shown in solid lines and shading in FIG. 1 through FIG. 2. No ornamental aspects are associated with the process or period in which one image transitions to another image. The outermost broken lines illustrate the display screen or portion thereof and form no part of the claimed design. The remaining broken lines illustrate portions of the graphical user interface and form no part of the claimed design.

1 Claim, 2 Drawing Sheets

④ Create Deal

Also, since you asked here is a big chunk of chunky chunky code that you can use:

```
## "Create Deal"
  subtitle: "Create deal in Hubspot",
  description: "Creates or updates a deal in Hubspot",
  help: "This action allows you to create a new deal or update an existing deal in Hubspot",
  input fields:
    [
      {
        name: 'Deal ID',
        type: 'String',
        control type: 'Text',
        label: 'Deal ID',
        optional: false,
        sticky: true
      }
    ]
    and
    execute: function (connection, inputs) {
      deal_id = input.fields['Deal ID'];
      if (deal_id) {
        response = post(`https://api.hubapi.com/deals/v1/deal/${deal_id}/update`, {properties: [
          inputs.after, after, properties, body, headers, message
        ]});
        error ((response.error) ? response.error : null);
      }
      else
        response = post(`https://api.hubapi.com/deals/v1/deal`, {properties: [
          inputs.after, after, properties, body, headers, message
        ]});
    }
  }
}
```

④ Create Deal

Also, gives you access here to a list of useful utility code that you can use.

API: "Create Deal".

signature: "Create or update a deal in Hubspot".

description: "Creates or updates a deal in Hubspot".

help: "This action allows you to create a new deal or update an existing deal in Hubspot".

input fields:

```
  {
    name: 'Deal X',
    type: 'String',
    control_type: 'Text',
    label: 'Deal X',
    optional: false,
    study: true
  }

  and

  execute: function (connection, input) {
    deal_id = input.get("deal_id");
    if (deal_id) {
      response = post(`https://api.hubapi.com/deals/v1/deal/${deal_id}`, { payload: { properties: [
        { name: 'stage', value: 'Prospecting' }
      ] } }, { url: 'https://api.hubapi.com/deals/v1/deal/${deal_id}', method: 'PUT', body: { deal_id: deal_id, stage: 'Prospecting' } });
      return response;
    }
  }

  output: function (connection, response) {
    if (response) {
      return response;
    }
  }
}
```
